UNITED STATES PATENT OFFICE.

ALVIN G. SMITH, OF HEMPSTEAD, NEW YORK.

AUTOMOBILE-LAMP.

1,193,438.

Specification of Letters Patent.

Patented Aug. 1, 1916.

Application filed March 4, 1916. Serial No. 82,076.

To all whom it may concern:

Be it known that I, ALVIN G. SMITH, a citizen of the United States, and a resident of Hempstead, in the county of Nassau and State of New York, have invented a new and Improved Automobile-Lamp, of which the following is a full, clear, and exact description.

This invention relates to electric lamps and has particular reference to headlights for automobiles or other vehicles.

Among the objects of the invention is to provide an improved construction of headlight whereby the glare therefrom may be reliably controlled without minimizing the effectiveness of the light for driving purposes.

A further object of the invention is to provide an improved reflecting structure adapted to concentrate the light upon the roadway downwardly and forwardly in front of the vehicle, but adapted to prevent all glare from the lamp, especially from its upper portion, that would tend to be objectionable to parties approaching the vehicle carrying the lamp.

Another object of the invention is to provide means in the nature of an attachment for common or standard forms of lamps whereby the several advantages of the improvement may be utilized by application to lamps now in use and without material or extensive change.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a front elevation of the new form of lamp casing, a portion being broken away to indicate the structure; Fig. 2 is a vertical longitudinal view of the same on the line 2—2 of Fig. 1; Fig. 3 is a front elevation of a modification adapted for connection to a standard lamp of conventional form; Fig. 4 is a vertical longitudinal section of the same on the line 4—4; and Fig. 5 is a sectional detail on the line 5—5 of Fig. 4.

Referring now more particularly to the

first two figures I show a main supporting casing 10 having a novel and characteristic form especially at its upper portion, being flattened as viewed from the front, for economy of space. The lower portion of the casing may, in the main, simulate the form of the conventional headlight casing. At the front of the casing 10 is connected in any suitable manner a lens plate comprising a rim 11 shaped to fit snugly upon the front edge 12 of the casing 10 and shown herein as secured in place by means of a pair of hinge pins 13, either of which may constitute a hinge pivot when the other pin is removed, or both of which may be removed for the purpose of removing the lens plate as a whole. The lens plate also includes an opaque member or shutter 14 closing all that portion of the front above the focal axis of the casing and locked to the rim 11 by any suitable means such as an internal rim 15. In the lower portion of the lens plate is secured a lens or transparency 16 of any suitable character, the same being substantially semi-circular in form.

The principal element of the improvement consists of a reflector of peculiar form secured within the casing and adapted to project the light forwardly from the lower half of the casing quite similar to the action of an ordinary parabolic reflector but with the upper portion of the reflector so constructed that it serves to project the light downwardly and thereby intensifies the light on the roadway directly in front of the vehicle. This reflector indicated at 17 may be described as consisting of a section of a parabola, the upper half of which is mashed downwardly toward the longer axis of the geometric figure. In fact, the central point of said upper half at 18 lies substantially in said longer axis or what would correspond to the focal axis of an ordinary parabolic reflector. It will thus be seen that the ceiling or upper portion of the reflector approximates a plane at 19, the same being inclined forwardly and downwardly from the focal portion 20 of the reflector. The whole of the interior surface of the reflector 17 constitutes a reflecting surface.

At 21 is a socket in which a lamp L of any suitable nature may be fitted, and the usual wires 22 lead thereto through an opening 23 in the outer casing.

The front edge of the reflector 17 is bent outwardly to form a flat flange 24 which

extends around parallel to the rim of the lens 16. A ring or gasket of felt or other suitable soft compressible packing material, shown at 25, is placed between the flange 24 and the internal rim 15, such gasket making a tight fit between the reflector and the lens plate, thereby excluding dust from the reflector and preventing rattling of the structure, such connection being made effective by the closing of the lens plate after the other parts of the device are adjusted.

At 26 I provide a cross bar extending horizontally across the front or mouth portion of the casing just back of the lens plate and against which the rear face of the upper portion of the flange 24 is adapted to squarely abut. A pair of braces 27 extend from the end portions of the cross bar upwardly and rearwardly to the top of the main casing 10 to which they are connected at the point 28. At the lower portion of the casing is arranged a lug 29 in the vertical plane of the cross bar 26 against which the lower portion of the flange 24 abuts. A screw threaded shank 30 is anchored at 31 to the extreme rear portion of the reflector 17 and extends thence rearwardly along the focal axis of the casing and lastly outwardly through an opening 32 in the main casing 10. An internally threaded sleeve 33 having a shoulder 34 is projected inwardly through the opening 32 and by coöperation with the shank 30 tends to draw the reflector rearwardly, causing the flange portion 24 thereof to bind snugly against the stop means 26 and 29 above described, the shoulder 34 bearing squarely against the outer surface of the casing for this purpose.

With the parts assembled as shown and described above, the light from the lamp passing downwardly acts upon the lower portion of the reflector 17, the same as in any other parabolic reflector, said light being projected forwardly in parallel lines as indicated at *a*. Thus the effect of the reflector with respect to all parts thereof below the horizontal plane of the focal axis *b* of the casing is substantially the same as in any other lamp having a parabolic reflector. All of the glare that is incident, however, to the light emerging from the upper half of a parabolic reflector of ordinary construction is shut off by the shutter 14. The rays of light from the lamp toward the upper portion of the reflector 19 are given either but a single reflection, as indicated at *c*, outwardly and downwardly upon the roadway in front of the vehicle, or else they are reflected to the lower portion of the reflector and thence given a second reflection, as indicated at *d*. The effect, therefore, of the upper portion of the reflector is either to concentrate a considerable portion of the light directly upon the roadway in front of the vehicle, or to provide a moderate amount

of diffused light without the accompanying glare.

In the modified form of the invention I show its adaptation to a conventional or standard form of lamp casing 10' having a parabolic reflector 17' secured therein in any approved manner and having a lens plate constituting a closure for the lamp casing and comprising a rim 11' and a window 16'. According to the usual practice a lamp L is secured in the socket 21 in the focus of the reflector and wires 22, as above described, lead thereto through the main casing. To adapt my improvement to a standard lamp of this character I remove the lens plate and secure in the upper half of the front opening of the lamp a shutter 14' which obstructs the rays of light from the upper half of the reflector 17'. The light from the lamp L passing downwardly therefrom and outwardly from the lower half of the reflector has the same effect as before described, passing in parallel rays forwardly in a beam. Above the lamp, however, I provide a reflector 19' of approximately flat form and having an attached concave hood 20' shown as of substantially hemispherical form and having a slot 35 which straddles the lamp socket 21. The reflector 19' is secured adjustably to the shutter 14', the same being indicated as hinged along a horizontal axis 36. The hinge is shown as comprising a pair of straps adjacent each end of the reflector, one of the straps 37 being connected to the rear surface of the shutter and the other 38 being connected by a dove-tail connection to a rib 39 extending along the upper surface of the reflector 19'. The hubs 37' and 38' are preferably serrated, as shown best in Fig. 5, so as to make a positive adjustment of the reflector up or down to provide a proper angle for the light reflected thereby, and this adjustment, together with the longitudinal adjustment of the reflector and ribs 39 along the dove-tailed arms or straps 38, adapts the attachment for various sizes or specific designs of standard lamps without material change or alteration. The longitudinal adjustment is made secure by means of set screws 40 or their equivalent. The slot 35 provides not only that the hood portion 20' of the device may be placed behind the lamp, but provides for the vertical adjustment of the upper reflector as may be required. In both forms of the invention shown, I provide for reflecting means, the lower portion of which is parabolic and the upper portion of which serves to throw the light forwardly and downwardly to concentrate the same upon the roadway directly in front of the vehicle, or to provide a moderate diffused light as a result of double reflection.

I claim:

1. In an automobile lamp, the combination

- with a main casing and a source of light carried within the casing, of reflecting means to receive the rays of light passing upwardly and downwardly from the source of light, 5 the lower portion of the reflecting means being parabolic and the upper portion of the reflecting means being relatively flat and inclined forwardly and downwardly and serving to concentrate a portion of the light received by it downwardly in front of the vehicle, and means to adjust the upper portion of the reflecting means vertically with respect to the main casing and source of light. 10
2. In an automobile lamp, the combination with a main casing and a source of light carried therein, of reflecting means for the light, the same comprising a parabolic reflector below the source of light and a reflector of a flat nature inclined forwardly 15 and downwardly and having its front edge portion terminating about the focal axis of the lamp, and supporting means for the latter mentioned reflector providing for both longitudinal and vertical adjustment thereof
- with respect to the main casing and source 25 of light.
3. In an automobile lamp, the combination of a main casing, a source of light carried therein, reflecting means for the light, said reflecting means being parabolic below the 30 focus of the light and serving to project the rays of light forwardly unobstructedly in parallelism from the casing throughout that portion thereof below the focal axis of the lamp, a shutter carried within the upper 35 portion of the casing at the front thereof and serving to close that portion of the casing above the focal axis, the upper portion of the reflecting means being located in the rear of said shutter and being inclined forwardly and downwardly with its front edge coinciding approximately with the lower edge of the shutter, and means to secure the reflecting means in position in the casing. 40
